UNITED STATES PATENT OFFICE.

NICHOLAS JACOVATOS, OF NEW YORK, N. Y.

CIGARETTE-BOX.

1,158,132.

Specification of Letters Patent. Patented Oct. 26, 1915.

Application filed June 12, 1914. Serial No. 844,621.

To all whom it may concern:

Be it known that I, NICHOLAS JACOVATOS, a citizen of the United States of America, and a resident of New York, in the county 5 and State of New York, have invented certain new and useful Improvements in Cigarette-Boxes, of which the following is a specification.

This invention has reference to improvements in cigarette boxes.

It pertains particularly to cigarette boxes which are usually made of paper and thrown away when all the cigarettes that were contained therein have been used up.

15 The cigarette boxes as commonly used consist essentially of a small paper box with the cover permanently attached thereto. The cover thus always retains its position relative to the box. Other cigarette boxes hold the cigarettes under a rubber band. When taking out a cigarette of such boxes it is easily damaged because cigarettes contain finely cut tobacco rolled up in an envelop which also is of a rather delicate 20 character. Such cigarette boxes may be opened in the usual manner by raising the cover and taking out a cigarette which is inconvenient and the cigarette is usually slightly damaged. Cigarette boxes of thin 25 metal sheeting suffer from the same defect and inconvenience.

The present invention has for its object, to avoid the described defects, and to produce cigarette boxes which permit of the removal 30 of a cigarette, without injuring the same. This has been primarily attained by constructing the cigarette box of two loose parts, a bottom and a cover which are hinged in one point only. This enables the user to 35 lift the cover of the box in the usual manner or shift it laterally for about one half of the length of the box in either direction, leaving the box partly open so that cigarettes may be taken out in any way desirable, and in the second case, without exposing all the cigarettes.

40 Boxes made according to this construction may be manufactured very cheaply and care has been taken to produce a neat and desirable article as required for this purpose; all 45 as will be fully described hereinafter, with reference to the accompanying drawing in which:

Figure 1 represents in perspective view a

cigarette box embodying in desirable form 55 the present improvement. Fig. 2 is a cross section of the box on a somewhat enlarged scale. Fig. 3 is a longitudinal section on line 3—3 of Fig. 1 also on a somewhat enlarged scale. Fig. 4 shows on a greatly enlarged scale the hinge portion of the box.

Similar characters of reference denote like parts in all the figures.

In the drawing *a* represents the box made preferably of paper, thin card board, or of thin metal sheeting if so desired. The box is provided with a loose cover *b* made of the same material. The box and cover may be ornamented and provided with advertising matter in the usual manner. In the rear 70 wall *a*¹ of the box a wire *c* is fastened by means of its ends *c*¹ *c*² as shown best in Fig. 3. This wire extends horizontally throughout the entire length of the box and runs along its rear wall in close proximity to its 75 top portion. For the purpose of forming a slide hinge the rear central portion of the cover *b* has secured under its lower surface a loop *d* which surrounds the wire *c* and is adapted to travel thereon. The loop *d* is 80 made of fine metal sheeting and its free ends *d*¹ *d*² lie under the bottom surface of the cover. It is evident that the cover may be moved in a horizontal plane in either direction by means of the wire *c* in the top portion 85 of the rear wall of the box and the loop *d* secured in the rear portion of the cover. These elements thus form a slide hinge. In order to guide the cover at the front side, opposite the hinge, when sliding along the 90 box, the front box wall *a*² is only of half height. The cover *b* has a downward front edge *b*¹ which meets the top surface of said front side of the box. A strip *e* of card board is attached to the inner surface of the 95 front side *a*² of the box. The front edge *b*¹ of the cover *b* slides along the top portion of the strip *e* when the cover is moved out. As soon as the hinge loop *d* reaches an outer end of the wire *c* the cover has reached the 100 end of its movement in this direction. This also applies to the opposite side end of the box. Accordingly the cover may be moved out about one half of its length in either direction.

105 To take out a cigarette the user may open the box by lifting the cover in the usual manner, as indicated in Fig. 2 or he may

shift the cover sidewise as indicated in Fig. 1. This renders the use of the novel box very convenient.

I claim as my invention:

- 8 1. A cigarette box consisting of two loose parts, a box and a separate shiftable cover, means on the front side of the box and cover for holding the cover in position and for guiding it when shifted, and a slide hinge on 15 the rear of the box composed of a wire extending along its inner top portion, and a sheet metal loop secured centrally on the lower rear surface of the cover and adapted to slide on the wire in either direction.
- 18 2. A cigarette box consisting of two loose parts, a box having a reduced front side, a separate cover having a downward front edge meeting the reduced front side of the box, and sliding means, located partly on the 20 inner top portion of the rear wall of the box and partly under the lower surface of the

cover so that the cover is adapted to slide in either direction, and may be raised.

3. A cigarette box consisting of two loose parts, a box having a reduced front side, a 25 separate cover having a downward front edge meeting the reduced front side of the box, and a slide hinge composed of a wire secured in the box and extending along the inner top portion of its rear wall, and a sheet 30 metal loop secured centrally under the lower rear surface of the cover and adapted to slide on the wire in either direction permitting of opening the box by raising the cover and by shifting it sidewise in either direc- 35 tion.

Signed at New York, N. Y., this 11th day of June, 1914.

NICHOLAS JACOVATOS.
